JAR CAP REMOVER

Lester C. Scott, Green Brook Township,
Somerset County, N. J.

Application January 14, 1950, Serial No. 7,261

Term of patent 7 years

(Cl. D44—29.1)

To all whom it may concern:

Be it known that I, Lester C. Scott, a citizen of the United States, residing at Green Brook Township, county of Somerset and State of New Jersey, have invented a new, original, and ornamental Design for Jar Cap Removers, of which the following is a specification, reference being had to the accompanying drawing, forming a part hereof.

Figure 1 is a perspective view of jar cap remover, showing my new design;

Figure 2 is a front elevational view;

Figure 3 is a side elevational view; and

Figures 4 and 5 are cross-sectional views taken on lines 4—4 and 5—5 respectively of Figure 1.

I claim:

The ornamental design for a jar cap remover, as shown.

LESTER C. SCOTT.
